CLAIM

The ornamental design for a travel bag, as shown and described.

DESCRIPTION

FIG. 1 is a front, top perspective view of a travel bag, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is a perspective view of a cross sectional cut out of the travel bag, showing an interior of the travel bag. The broken lines in the figures illustrate portions of the travel bag that form no part of the claimed design.
